DESIGN FOR A FILTER FOR BEVERAGE BREWERS

Edward J. Ruhnke, Chicago, Ill., assignor to Hill-Shaw Company, Chicago, Ill., a corporation of Illinois

Application January 31, 1945, Serial No. 117,692

Term of patent 14 years

(Cl. D44—26)

To all whom it may concern:

Be it known that I, Edward J. Ruhnke, a citizen of the United States and a resident of Chicago, in the county of Cook and State of Illinois, have invented a new, original, and ornamental Design for a Filter for Beverage Brewers, of which the following is a specification, reference being had to the accompanying drawing, forming a part thereof.

I claim:

The ornamental design for a filter for beverage brewers, as shown.

EDWARD J. RUHNKE.
